UNITED STATES PATENT OFFICE.

CLARENCE A. BATES, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

ELECTRIC SWITCH.

1,127,379.

Specification of Letters Patent.

Patented Feb. 2, 1915.

Application filed December 30, 1913. Serial No. 809,569.

To all whom it may concern:

Be it known that I, CLARENCE A. BATES, a citizen of the United States of America, and residing at Bridgeport, in the county 5 of Fairfield and State of Connecticut, have invented a certain new and Improved Electric Switch, of which the following is a specification.

My invention relates to electric switches 10 and particularly to electric switches for house lighting.

The special object of my invention is to provide a switch of such construction that certain novel combinations of electrical connections may be established therethrough, 15 depending upon the position of the switch mechanism.

In the accompanying drawing, Figure 1 is a longitudinal section through a push 20 button switch in which my invention is illustratively embodied; Fig. 2 is a side elevation of the switch mechanism withdrawn from the switch receptacle and viewed from the opposite side; Fig. 3 is a sectional elevation of the latter on the line 3—3, Fig. 2; and Fig. 4 is a detached perspective of certain elements and showing a wiring system in connection therewith.

The present invention is here shown embodied in a push button snap switch of flush receptacle type, but it is to be understood that it may be embodied in switches of any desired suitable type. The porcelain receptacle body 10 is of well known cup form and 35 carries at each end two wire terminals 11 connected to contact straps 12, one for each of the spring straps 13, 14, 15, 16 mounted in well known manner upon the plug 17 of insulating material and adapted to friction- 40 ally engage and electrically connect with the wire terminal straps 12. Pairs of switch terminals 18 and 19, 20 and 21 are formed integral with or carried by the spring straps. Coöoperating therewith are the usual switch 45 bars 22, 23, mounted upon the spindle 24, and subjected to the snap action of the switch spring 25 through the depression of one or the other of the push buttons 26, 27 in well understood manner. The switch 50 bars and terminals are so arranged that connection between terminals 18 and 19 is broken when that between 20 and 21 is made, and vice versa.

It will be noted that terminal 18 is of

such length and shape that the wings of 55 switch bar 22 are constantly in engagement therewith, so that the effect is to secure a constant connection between switch bar 22 and terminal 18 in all positions of the switch. It will also be noted that the switch 60 bar 22 is electrically connected to bar 23 by a strap 28 passing over the usual oscillating yoke 29 but separated therefrom by the strip of insulation 30. The effect of this construction is to establish electrical connection between terminal 18 and terminal 19 in one position of the switch and between terminal 18 and terminals 20 and 21 in the other position of the switch. In the first case the connection is direct through the 70 switch bar 22. In the second case the connection is established through switch bar 22, strap 28 and switch bar 23. Assuming that the terminal 20 is of the same polarity as terminal 19, the current entering the switch 75 through 18 (assuming the latter to be the positive pole) passes out through 19 in one position of the switch and through 20 in the other position of the switch. There is thus a constant connection through the switch 80 from terminal 18 to one or the other of the terminals 19 or 20 depending upon the position of the switch bar. On the other hand, the terminals 20 and 21 being normal one-position contact terminals, the connection 85 between the same is either made or broken, depending upon the position of the switch bar 23.

The switch thus comprises four switch terminals, two for incoming and two for outgoing wires, and a snap switch mechanism having two positions, and comprising a pair of switch bars adapted to connect pairs of switch terminals, together with a cross connection between the switch bars by means of 90 which both incoming terminals are connected to one outgoing terminal in one position of the switch, while in the other position of the switch this connection is broken and one of the incoming terminals is connected to the 95 other outgoing terminal.

The switch is capable of various uses and I do not limit myself to any one in particular. In Fig. 4 a house wiring system is shown in which the lamps 1 to 4 are controlled by the switch in the "on" position, 100 while the lamp 1 is controlled by the remote control switch X when the local switch is

"off." Furthermore, the arrangement of connections is readily adapted to switches of other types, and the invention is not limited to the particular embodiment here illustrated.

Obviously the polarity of the terminals may be reversed without affecting the action of the switch.

I claim as my invention:

- 10 1. An electric snap switch having four switch terminals, two for incoming and two for outgoing wires, in combination with a two position switch mechanism comprising means for connecting both of the terminals or incoming wires with only one of the terminals for outgoing wires in one position of the switch and means for connecting only one of the terminals for incoming wires with the other terminal for an outgoing wire, in the second position of the switch, for the purpose described.
- 15 2. An electric snap switch having four switch terminals, two for incoming and two for outgoing wires, two movable switch blades both electrically and mechanically connected together and means for throwing the blades together to two different positions, in one of which three of the switch terminals are electrically connected and in the other of which two terminals of opposite polarity are electrically connected together.
- 20 3. An electric snap switch having four switch terminals and four wire connections therefor, in combination with two two-position contact blades mounted on a common axis and electrically and mechanically connected with each other and a snap switch

mechanism for shifting said contact blades from one position to the other, for the purpose described.

4. An electric snap switch having four switch terminals and four wire connections therefor, in combination with two two-position contact blades mounted on a common axis and electrically and mechanically connected with each other and a snap switch mechanism for shifting said contact blades from one position to the other, one of said switch terminals being of such construction that one of the switch blades makes contact therewith in both positions of the switch.

5. An electric snap switch having two pairs of switch terminals of opposite polarity in combination with a pair of switch blades mounted on a common axis and electrically connected together and cooperating with said pairs of switch terminals, one of said blades making and breaking contact between one pair of terminals in successive positions of the switch, the other of said blades making contact with one of the terminals of the other pair of switch terminals in all positions of the switch and connecting said terminal to the cooperating terminal of opposite polarity when the circuit between the first mentioned pair of switch terminals is broken, substantially as described.

In testimony whereof I have signed my name to this specification, in the presence of two subscribing witnesses.

CLARENCE A. BATES.
